UNITED STATES PATENT OFFICE.

HOWARD B. WASHINGTON, OF ST. LOUIS, MISSOURI.

HAIR-CUTTER.

1,183,330.

Specification of Letters Patent.

Patented May 16, 1916.

Application filed August 31, 1915. Serial No. 48,333.

To all whom it may concern:

Be it known that I, HOWARD B. WASHINGTON, a citizen of the United States, residing at St. Louis, in the State of Missouri, have invented certain new and useful Improvements in Hair-Cutters; and I do hereby declare the following to be a full, clear, and exact description of the invention, such as will enable others skilled in the art to which it appertains to make and use the same.

This invention relates to hair cutters, and the primary object of the invention is to provide a cutter which includes a comb, a supporting body and a cutting blade connected for forming a cutter, by means of which the hair of a person's head may be cut by himself, with the same operation as would be necessary for combing the hair.

Another object of this invention is to adjustably mount the cutting blade, so that the length of the hair, which is left upon the head, may be regulated, as desired.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:—

Figure 1 is a perspective view of the improved hair cutter, Fig. 2 is a cross sectional view through the hair cutter, Fig. 3 is a side elevation of the hair cutter, showing parts broken away, Fig. 4 is a detail perspective view of one end of the knife carrying frame, Fig. 5 is a fragmentary bottom plan view of the cutter.

Referring more particularly to the drawings, 1 designates the body of the hair cutter, which is composed of a piece of sheet metal, which is rolled intermediate its ends, as is shown at 2, and has a horizontal portion 3 against which the back of an ordinary comb 4 rests. The edge 5 of the body 1, remote from the edge 3, is curved inwardly and engages the back of the comb upon the opposite side of the comb which is engaged by the section 3.

The body 1 has blocks or plates 6 and 7 secured to its ends, which blocks are provided with a plurality of spaced parallel and inclined extending slots 8 formed in

their facing sides. The slots 8 are provided for receiving the tongues or projections 10 which are formed upon the bottom plate 11 of the knife carrying structure 12. The knife carrying structure 12 includes, besides the bottom plate 11, a plate 14, which is spaced from the bottom plate 12 and has tongues 15 formed upon its ends, which tongues are bent downwardly at right angles 65 to the plate 14, and have their terminals bent parallel to the plate, as is shown at 16, forming ears for engagement with the under surface of the ends of the cutting knife 17. The tongues 15 extend downwardly 70 between the tongues 10, which are formed upon the plate 11.

The plate 14 is provided with an enlarged portion 18, which is positioned centrally of its ends, and which is screw threaded. A 75 thumb screw 19 is carried by the screw threaded enlarged portion 18, and extends therethrough, having its inner end positioned in engagement with the surface of the plate 11, so that when the thumb screw 80 19 is rotated, the plates 11 and 14 will be spread, causing the ears 16 to firmly grip the under surface of the cutting blade 17 and hold the same in firm engagement with the under surface of the plate 11. 85

The plate 1 is provided with openings 20 formed in the side 3 of the same adjacent its ends. In case a comb is used in which the rear edge of the back of the comb is not straight, a pin indicated at 21 in Fig. 5 of 90 the drawings may be attached to one of the ends 6 or 7 and project a short distance outwardly from the same, forming a rest against which the end of the back of the comb will rest, for causing the points of the 95 teeth of the comb to lie in a plane parallel with the cutting edge of the knife 17. The blocks 6 and 7 are substantially rectangular in shape, and have their edges, which extend angularly from the edge against 100 which the ends of the comb engage, arcuate, as is clearly shown at 22, so as to prevent the irritation of the person's scalp during the cutting of the hair.

In the operation of the improved hair cutter, the cutting blade carrying structure 12 is adjusted, by placing the tongue 10 in any one of the slots 8, so that the desired distance between the edge of the comb and the cutting edge of the blade may be maintained, for 110 gaging the length of the hair of the operator's head after it has been cut. The cutter

is then drawn over the head of the operator in the same manner in which his hair is combed, preferably against the grain at the first cutting and with the grain at the second cutting, thereby efficiently cutting the operator's hair in the same manner in which it is combed.

From the foregoing description taken in connection with the accompanying drawings

- 10 the advantages of construction and of the method of operation of the improved hair cutter will be readily apparent to those skilled in the art to which this invention appertains and, while in the foregoing description, the principle of the operation of this invention has been described together with various features of construction, it is to be understood that certain minor features of construction, combination and arrangement 15 of parts may be altered to suit practical conditions provided such alterations are comprehended within the scope of what is claimed.
- 20

What is claimed is:—

- 25 1. In a hair cutter, the combination, of a body portion, end plates mounted upon the ends of said body portion and projecting upwardly therefrom, an ordinary comb detachably carried by said body portion, said end plates being provided with a plurality of
- 30

spaced parallel extending inclined slots, a knife carrying structure having tongues formed upon its ends for insertion into said slots, a knife detachably carried by said knife carrying structure, said tongues adapted for insertion into various of said slots for holding said blade carrying structure and said blade at any desired distance from said comb.

2. In a hair cutter, the combination, of a 40 body portion, a comb detachably carried by said body portion, end blocks mounted upon the ends of said body portion and being provided with a plurality of spaced parallel extending inclined slots, a knife carrying structure including a bottom plate, a second plate adjustably connected to said bottom plate, a cutting blade, means carried by said adjustable plate for engaging said cutting blade and binding it against the under surface of said bottom plate, tongues formed upon the ends of said bottom plate for insertion into said slots.

In testimony whereof I affix my signature in presence of two witnesses.

HOWARD B. WASHINGTON.
